(57) **CLAIM**

The ornamental design for a dispenser, as shown and described.

DESCRIPTION

FIG. 1 is an isometric view of the top, front, and right side of the dispenser embodying my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is an isometric view of the top, front, and right side of an alternate embodiment of my design for a dispenser;
FIG. 8 is a front elevational view thereof;
FIG. 9 is a rear elevational view thereof;
FIG. 10 is a left side elevational view thereof;
FIG. 11 is a right side elevational view thereof; and,
FIG. 12 is a top plan view thereof.

The dash-dash-dash lines are included for the purpose of illustrating portions of the dispenser that form no part of the claimed design. The dash-dot-dash lines are included for the purpose of illustrating boundary lines that form no part of the claimed design.
